Attorney

UNITED STATES PATENT OFFICE.

JOHNN GREINER, OF BALTIMORE, MARYLAND.

RAIL JOINT.

Application filed December 1, 1925. Serial No. 72,462.

To all whom it may concern:

Be it known that I, JOHNN GREINER, a citizen of the Republic of Germany, residing at Baltimore and State of Maryland, have 5 invented certain new and useful Improvements in a Rail Joint, of which the following is a specification.

This invention relates to railway rails, and has more particular reference to a 10 joint construction between the meeting ends of the rail sections.

The primary object of my invention is to provide a rail joint wherein the necessity of employing connecting fish plates, chairs 15 and the like will be dispensed with and wherein vibrations of the adjacent rails with respect to each other will also be substantially overcome and preventing the dis-alinement of the meeting of the rails in both 20 horizontal and vertical directions which is a disadvantage in the present type rail joint.

A further object is to provide a joint wherein the adjacent ends of the rail section may be rapidly and efficiently secured together without requiring bolts, or other similar connections.

With the foregoing and other objects in view as the nature of the invention will be better understood, the same comprises the 30 novel form, combination and arrangement of parts hereinafter more fully described and shown in the accompanying drawing and claimed.

In the drawing, wherein like reference 35 characters indicate corresponding parts throughout the several views:—

Figure 1 is a fragmentary side elevation of a pair of rail sections interconnecting through the medium of my present joint.

Fig. 2 is a bottom plan view thereof,

Fig. 3 is a horizontal section through the joint, and

Fig. 4 is a perspective of the rail end interconnecting member.

Now having particular reference to the drawing, there are disposed a pair of rail sections 5—5 that are adapted to be interconnected in end to end relation.

In carrying out my invention, the opposite ends of these rail sections have their web portions enlarged at opposite sides of the sections as indicated at 6—6, the enlargement being preferably of such thickness as to extend flush with the tread of the rail section as clearly shown in Fig. 1.

Extending through the base of each rail section at its end and into the thickened portion thereof are spaced vertical slots 7, 8 and 9, that are preferably of various widths as shown in Fig. 2, that are in communication with each other and separated by similarly spaced ribs 10—10 and 11—11, said ribs being preferably of a width complementary to the width of the slots at the inner sides thereof.

The outer slots 9 of the rail sections open at the edges of the rail section, and extending thereacross at the lower edge of the enlarged web portion are slots 12, Fig. 1.

The joint further includes the provision 70 of an interlocking bar or plate shown clearly in Fig. 4 and designated generally 13. This interlocking bar is formed at its opposite ends with spaced key plates 7'—7 and 8'—8' of substantially similar dimensions 75 as the slots 7 and 8 in the opposite ends of the rail sections, the same being interconnected through the medium of webs 10'—10'. Intermediate the ends of the locking bar the same is provided with a relatively wide key 80 plate 9' of substantially similar dimensions to the outermost slot 9 of the rail sections when said rail sections have been placed in end to end relation as shown in Fig. 2. This intermediate key plate is formed centrally with a cross slot 12' which is also of 85 substantially similar dimension with the cross slots 12 in the ends of the rail sections when the same have been placed in end to end relation.

It will thus be seen that the key member 13 may be readily slid upwardly into the slots of the rail sections when the same have been brought into end to end relation for manifestly maintaining the rail sections in 90 joined relation and absolutely preventing any transverse movement of the rail sections with respect to each other as well as any longitudinal movement thereof.

After the key member has been properly 100 inserted intermediate the ends of the rail sections, a key pin 14 is passed through the slots 12 in the rail sections and slot 12' in the member 13. One end of this pin is headed as at 15, while the opposite end 105 thereof is provided with fingers 16—16 that may be bent at right angles to the key against the adjacent web portions of the rails for preventing accidental disengagement of the member 14 from the member 110

13 and rail sections. This key 14 will effectively lock the member 13 within the adjacent ends of the rail sections and also prevent any vertical movement of the sections with respect to each other.

It will thus be seen that I have provided a novel, simple and efficient form of rail joint that is well adapted for all of the purposes intended, and even though I have herein shown and described the most practical embodiment of the invention with which I am at this time familiar, it is nevertheless to be understood that minor changes may be made therein without departing from the spirit and scope of the appended claim.

Having thus described my invention, what I claim as new and desire to secure by Letters Patent is:

20. In a joint for the meeting ends of rail sections wherein said rail sections are formed at their opposite ends with thickened web portions flush with the tread of the sections, said thickened portions being provided with spaced vertical slots terminating at one end within the thickened portion and at their opposite ends through the rail bases, spacing ribs between the slots,

30 the outermost slots of the sections being provided with cross slots at the base of the rail sections, an interlocking bar provided at its opposite ends with locking plates interconnected through the medium of webs, said plates adapted to engage upwardly within the innermost slots of the rail section, said interlocking member being formed intermediate its ends with an additional locking plate for engagement within the outer slots of the rail sections and being provided with a cross slot complementary 40 to the cross slots of the outer web slots of said rail sections, and a locking member adapted to be disposed through the slots of the intermediate locking plate of said member and the cross slots of the rail sections, 45 for maintaining the locking member in association with the slots in the rail sections, said last mentioned member being headed at one end and provided at its opposite end with fingers that are adapted to be bent at 50 right angles with respect to the member alongside of the webs of the rails for preventing accidental disengagement of the member from said slot.

In testimony whereof I affix my signature
JOHNN GREINER.
